UNITED STATES PATENT OFFICE.

IVAN P. VUGRINOVIC, OF INDIANA HARBOR, INDIANA.

PADLOCK.

1,149,230.

Specification of Letters Patent. Patented Aug. 10, 1915.

Application filed January 12, 1915. Serial No. 1,836.

To all whom it may concern:

Be it known that I, IVAN P. VUGRINOVIC, a subject of the Emperor of Austria-Hungary, residing at Indiana Harbor, in the county of Lake and State of Indiana, have invented certain new and useful Improvements in Padlocks; and I do hereby declare the following to be a full, clear, and exact description of the invention, such as will enable others skilled in the art to which it appertains to make and use the same.

This invention relates to pad locks and more particularly to a keyless pad lock.

The invention has for its object to provide a lock of generally improved and simplified construction embodying a pivoted shackle adapted to be retained in closed position by a sliding tumbler operable by gravity when the lock is moved into proper position.

Another object is the provision of a pad lock embodying a gravity operable sliding tumbler and means controlled by the shackle for locking the sliding tumbler against movement.

With these and other objects in view, the invention consists in the novel construction, arrangement and formation of parts as will be hereinafter specifically described, claimed and illustrated in the accompanying drawings, in which:

Figure 1 represents a front elevation of the pad lock. Fig. 2 represents a side elevation thereof. Fig. 3 represents a front elevation, partly broken away, of the pad lock, showing the front or cover plate removed, and, Fig. 4 represents a longitudinal sectional view through the pad lock, partly broken away.

Referring to the drawings in detail, wherein similar reference numerals designate corresponding parts throughout the several views, the numeral 10 indicates the body of the lock having a plurality of recesses therein for receiving the parts of the lock mechanism which are covered by the cover or front plate 11 suitably secured to the front face of the body 10. The top of the body 10 is formed with recesses receiving the opposite ends of the curved shackle 12, one end of which is enlarged and apertured, as indicated at 13, to receive the pivot pin 14 secured to the rear wall of the body 10 and the cover plate 11. The enlarged end

13 of the shackle is formed with a radially extending pin 15 over which is engaged one end 55 of a coil spring 16 seated in a suitable recess in the body 10 and normally tending to swing the pivoted shackle 12 to open position. The opposite end of the shackle is formed with a transverse opening 17 adapted to receive the sliding tumbler to be hereinafter described.

The body 10 is formed with a diagonal chamber or recess 18 extending in alignment with the aperture 17 in the free end of the shackle and intersecting the recess in the body receiving the free end of said shackle. A tumbler 19 is slidably mounted in the diagonal recess or chamber 18 and is adapted, when the lock is tilted, to slide through 70 the aperture 17 in the free end of the shackle 12 to lock the latter in closed position. A second chamber or recess 20 is formed in the body 10 at right angles to the recess 18 and receives the slidable locking bar 21 having 75 a pair of spaced teeth 22 formed laterally thereof. A lever 24 is pivoted at 25^a in the body 10 and the short end thereof engages the free extremity of the pivoted shackle 12 and the long end or arm thereof is 80 normally retained in inwardly extended position by the tension of a spring 25. The long end of the lever is also normally retained in the path of the enlarged and weighted end of a pawl 26 pivotally secured at 27 in 85 the body or casing 10 and having a tooth 28 engaging between the teeth 22 of the slid- able locking bar 21.

In use, when it is desired to release the pivoted shackle 12, the latter is moved inwardly a short distance on its pivotal axis 14 thus swinging the lever 24 upon its axis 25, moving the long end thereof out of the path of the weighted enlargement 26 of the pawl. The pad lock is subsequently inverted and the weight 26 swings the tooth 28 of the pawl by gravity into mesh with the teeth 22 of the bar 21, thus sliding the latter longitudinally to permit the sliding tumbler 21 to move inwardly. It will be 100 understood that when the lever 24 is in normal position the long end thereof is disposed in the path of the weighted end 26 of the pawl and the latter is not permitted sufficient movement to operate the slide bar 105 21. By tilting the pad lock in the proper

position and slightly depressing the pivoted shackle 12 the sliding tumbler 19 slides into the chamber 18 and thus releases the shackle permitting the latter to open under the influence of the spring 16.

5 What I claim is:

1. A pad lock comprising a body, a curved shackle pivotally secured at one end in said body, a sliding tumbler securing the free 10 end of said shackle in closed position, and spring means connected directly with and normally tending to open said shackle, and retaining the latter in frictional engagement with said sliding tumbler to prevent

15 loose movement thereof.

2. A pad lock comprising a body, a curved shackle pivotally secured at one end in said body, means normally tending to open said shackle, a sliding tumbler for locking the 20 free end of said shackle in closed position, a slide bar for retaining said sliding tumbler in extended or locked position, gravity operable pawl controlling said slide bar, and means controlled by the free end of said 25 shackle for limiting the movement of said pawl.

3. A pad lock comprising a body, a shackle pivotally secured at one end to said body, a sliding tumbler adapted to coöperate 30 with the free end of said shackle to lock the latter in closed position, a slidable bar for locking said sliding tumbler in locked position, gravity operable means associated with said slidable bar, and spring means controlled by the free end of said shackle 35

for limiting the movement of said gravity operable means.

4. A pad lock comprising a body, a curved shackle pivotally secured to said body, a sliding tumbler for engaging and locking 40 the free end of said shackle in closed position, a slidable bar for locking said tumbler in extended or locked position, gravity operable means associated with said slidable bar, a lever pivotally mounted in said body for 45 limiting the movement of said gravity operable means, and means normally retaining said pivoted lever in the path of said gravity operable means.

5. A pad lock comprising a body, a 50 shackle pivotally secured in said body, a sliding tumbler adapted to coöperate with the free end of said shackle to lock the latter in closed position, a slidable bar for locking the tumbler in locked or extended position, gravity operable means associated with said sliding bar, a lever pivotally mounted in said body engaged at one end with and operable by the free end of said shackle and having the opposite end disposed in 55 the path of said gravity operable means to limit the movement of the latter, and means normally retaining the end of said lever in the path of said gravity operable means.

In testimony whereof I affix my signature 60 in presence of two witnesses.

IVAN P. VUGRINOVIC.
